CLAIM

The ornamental design for a lawn mower as shown and described.

DESCRIPTION

FIG. 1 is a perspective view of a lawn mower showing our new design.

FIG. 2 is a right side view thereof.

FIG. 3 is a left side view thereof.

FIG. 4 is a front view thereof.

FIG. 5 is a back view thereof.

FIG. 6 is a top view thereof; and,

FIG. 7 is a bottom view thereof.

In the above drawings the broken lines and the areas within the broken lines form no part of the claimed design.
